UNITED STATES PATENT OFFICE.

HERMANN LEMP, OF LYNN, MASSACHUSETTS, ASSIGNOR TO GENERAL ELECTRIC COMPANY, A CORPORATION OF NEW YORK.

ELECTRIC AUTOMOBILE.

SPECIFICATION forming part of Letters Patent No. 692,874, dated February 11, 1902

Application filed November 2, 1900. Serial No. 35,253. (No model.)

To all whom it may concern:

Be it known that I, HERMANN LEMP, a citizen of the United States, residing at Lynn, county of Essex, State of Massachusetts, have 5 invented certain new and useful Improvements in Electric Automobiles, (Case No. 1,647,) of which the following is a specification.

The present invention relates to electrically-propelled vehicles, and while it is shown in connection with a vehicle receiving its current from a storage battery it is within the scope of my invention to utilize it in connection with stationary conductors for supplying current to a contact device mounted on the vehicle for engagement therewith.

The invention has for its object to improve the construction and operation of electrically-propelled vehicles, as will be more fully described and claimed hereinafter.

In the accompanying drawings, Figure 1 is a side elevation of a self-propelled vehicle. Fig. 2 is an end elevation of a motor and clutch mechanism; Fig. 3, a partial side elevation of the motor and clutch mechanism. Fig. 4 is a sectional view taken on line 4-4 of Figs. 2 and 5. Fig. 5 is a transverse section through the clutch and worm-driving mechanism. Figs. 6 and 7 are detail views of the 25 clutch. Figs. 8 to 13, inclusive, are diagrams of the circuit connections; and Fig. 14 is a development of the controller-cylinder.

In operating electrically-propelled vehicles it is desirable to employ a high-speed motor or motors and to gear said motor or motors to the driving wheel or wheels by a mechanism which will make little or no noise. It is preferable to use a motor in which the reduction of speed between the armature and the 35 driving-wheel is about twenty to one. If such motor is employed, considerable weight may be saved or a greater efficiency may be secured for the same weight. The only satisfactory means of transmission for such high reductions is worm-gearing. With worm-gearing when the ratio of transmission is greater than eight to one the angle of the worm is such that it cannot be driven backward. In other words, the vehicle can be driven by the 40 motor-armature; but the worm cannot drive the armature when the power is cut off and the

vehicle permitted to coast. With a greater ratio of gearing than one to eight if power were suddenly cut off, due to accident or otherwise, it would either destroy the working 55 mechanism or stop so suddenly as to throw the occupants out of the vehicle.

I overcome the objection above pointed out by utilizing an electrically-actuated clutch, which clutch is provided with an energizing-coil that is in series with the propelled motor or motors. The clutch is preferably designed to lock the motor-armature to the driving mechanism as distinguished from those clutches in which a certain amount of slip is 60 permitted and desired. If, however, it is desired to get an intermediate regulation differing from that afforded by the controller or for any other reason, the clutch can be arranged to slip. With an arrangement of 65 either kind when the current is cut off from the motor or motors the gearing between the motor and the driving wheel or wheels is disengaged and the vehicle is free to coast. A satisfactory arrangement is to suspend the 70 motor from the vehicle-body in a vertical position, with the worm on the armature-shaft acting on the front side of a worm-wheel carried by or secured to the driving wheel or 75 wheels. Preferably the clutch for controlling the mechanism is of a type in which the exciting-coil is stationary and mounted on a 80 stationary axle, while the magnetic keeper or armature is a part of the driving-wheel. Of course a moving coil may be used whenever 85 any advantage would follow therefrom.

Referring to Fig. 1, A represents the body of the vehicle, B the steering-wheels, and C the driving-wheels. The steering is accomplished through the handle D, and the speed 90 of the motors is regulated by the controller E, which is located under the seat of the vehicle and is provided with an operating-handle that is conveniently located at one side of the operator's seat. The braking is accomplished through a foot-operated lever F, that actuates a band-brake F' on a hub carried by the driving-wheels. The vehicle-body is supported by two full elliptic springs at the rear, which extend parallel with the direction of 95 travel of the vehicle, and at the front by a single transverse spring. The upper sides of 100

the rear body-springs are secured by clamps G', that are bolted to the frame of the carriage-body. The lower half of each of these springs is mounted in a socket G², that is 5 formed on the upper side of the fixed casing H, which surrounds the driving-worm and worm-wheel.

The rear axle is stationary, and rigidly secured thereto is a cylindrical casing H. This 10 casing incloses the driving mechanism, as will be hereinafter described. Located above the casing is a small high-speed motor I. This motor is mounted in such a manner that the armature-shaft extends in a vertical direction 15 at right angles to the plane of the axle. The motor is supported by means of a boss or projection H', that is formed on the casing H, which boss or projection also surrounds the armature-shaft and forms a bearing therefor. Formed integrally with and on the front end of the motor are two lugs I', and passing through these lugs and also through a supporting-bracket J, which is secured to the under side of the vehicle-body, 20 is a rod or bolt K. Surrounding this bolt and located, respectively, above and below the bracket are coiled springs K' for taking up the thrust of the motor as it tends to twist around the rear axle as a center. On the lower end 25 of the armature-shaft is a worm I², engaging with the worm-wheel I³, the latter being rigidly connected to the armed spider L, which forms the keeper or armature of the clutch. The angle of the teeth on the worm and worm- 30 wheel is such that it is impossible for the vehicle to drive the armature of the motor, as in coasting, without some special means for disconnecting the parts as provided.

Referring more particularly to Figs. 4 to 7, 35 inclusive, M represents a stationary energizing-coil which is included in series with the motor whenever the latter is receiving current, as will be more fully described herein-after. A portion of the rear axle is made 40 hollow, and extending through the hollow portion of the shaft to the coil M are flexible leads M'. The driving-wheel C is provided with a hub having a disk-like portion N, with radial extending arms N', which surround the 45 coil and extend inward to a point where they can engage with the radial arms of the keeper L. Between the arms of the keeper and the arms N' is located a plate of non-magnetic material to prevent the arms from sticking. Sur- 50 rounding the portion of the clutch carried by the driving-wheel is a casing O, and secured to the casing or formed integrally therewith is a braking-surface O', with which the band F', Fig. 1, engages. The keeper L, which 55 carries the worm-driven wheel, is mounted on ball-bearings on the rear axle, so that it is free to turn. When the coil M is energized, the keeper L and the magnet N are attracted, and the tooth-like structure of these parts 60 causes them to be firmly locked together. Motion will then be imparted from the worm I² on the armature-shaft to the worm-wheel 65

I³ and to the keeper L, and thence to the armature N and the driving-wheel C. In the drawings only one driving-motor is shown; 70 but it is to be understood that a motor is employed for each of the rear driving-wheels. It is within the scope of my invention, how- 75 ever, to use only a single motor and to locate it in any desired position, and I aim to em- brace such a use in the claims. The feature of using two motors (one for each driving- 80 wheel) possesses certain advantages over the use of a single motor, and for that reason is more desirable; but my invention is not lim- 85 ited thereto.

Referring to Figs. 8 to 12, inclusive, P represents a source of energy, I³ and I⁴ the motor-armatures, and I⁵ the field-windings.

The controller E and the circuit-wires and 85 brushes therefor are illustrated in Fig. 14.

In Fig. 8 the batteries P are shown as connected in series. In series with the source of supply are two stationary clutch-coils M, one for each motor. When a single motor is 90 used, only one coil is needed. The current after passing through the clutch-coils passes through the field-windings of the motors in multiple series, and thence through the armatures of both motors and back to the source 95 of supply. This arrangement of circuits represents the lowest backward speed connec- 100 tions, and the coils M being energized lock the parts of the clutch together, and motion is imparted from both motors to the driving- wheels.

Referring to Fig. 9, the circuits are represented as they exist in the first forward and lowest speed running position. The batteries are shown as connected in multiple, and current therefrom passes through the clutch- 105 coils M in a direction opposite to that illus- 110 trated in connection with Fig. 8, after which it passes through the field-coils of the motors in multiple series, and thence through the armatures of both motors in series to the nega- 115 tive side of the battery.

In Fig. 10 the circuit connections have been modified to the extent of connecting the batteries in series, thereby increasing the effective electromotive force, and consequently the speed of the vehicle. The remainder of the connections are as illustrated in Fig. 9.

In Fig. 11 the circuit connections have been modified to the extent of connecting the armatures of the two motors in multiple instead of series. In other respects the connections are as above described.

In Fig. 12 the circuit connections are modified to the extent of connecting the motors in 125 multiple and cutting out approximately one- half of each field-winding. This is the highest speed combination of circuits. It will be seen that the clutches are operated irrespec- 130 tive of whether the vehicle is going forward or backward and also that they are in opera- tive condition just as soon as the circuit is closed. By including these clutch-coils in circuit with the motors and regulating them by

means of the speed-controlling device it entails no extra exertion or thought on the part of the operator, since it is taken care of automatically by the opening or closing of the circuit. When the vehicle comes to a point where it is desired to stop or to coast, the operator merely brings the controller-handle to the off position and the circuit of the clutch-coils is automatically interrupted and the driving-wheels being thus released from the driving-motors are free to turn, and as soon as the armature stops the worm-wheels will stop also and remain idle until the circuit of the motors is again completed. In order to stop the vehicle, the brake-lever F is actuated.

In Fig. 13 is shown two of the contacts E', which are carried by the cylinder of the controller E. Mounted for engagement with these contacts are brushes E², which are connected to the conductors leading to the magnet-coils M and the motors. For the sake of simplicity the remainder of the contacts and brushes have been omitted. The contacts E' are cross-connected, so that when they are brought from the off position, as shown, into engagement with the stationary brushes E² the circuit through the magnet-coils M, motors I³ and I⁴, and source of supply P is completed. It will thus be seen that the coils M always receive current when the motors are operating to propel the vehicle and this without thought on the part of the operator.

Fig. 14 shows the cylinder of the controller E developed, together with the necessary brushes and wires for coupling up the motors in the manner illustrated in Figs. 8 to 12, inclusive. When the contacts on the cylinder are moved to a point where the brushes rest on line 8 8, the batteries P are connected in series, as are also the armatures. Current then passes from the batteries P through the magnet-coils M in series, to the field-coils I⁵, through the latter in multiple, and thence through the armatures in series to the negative side of the batteries P. This arrangement of circuits gives the motor combination illustrated in Fig. 8 and is designed to cause backward rotation of the armatures. When the cylinder is advanced to a position where the vertical row of brushes rests on the line 9 9, the batteries P are connected in multiple and current flows therefrom through the magnet-coils in series, thence through the field-coils I⁵ in multiple, and through the armatures in series back to the batteries. With the parts arranged as described the motors are connected as shown in Fig. 9, which gives the first speed forward. When the contacts on the cylinder are advanced to a position where the vertical row of brushes rests on line 10 10, the batteries are coupled in series relation, the motor and clutch-coil connections remaining as before. With the parts arranged as described the motors are connected as shown in Fig. 10. Advancing the contacts to the point where the brushes rest on line 11 11 connects the motor-armatures in multiple relation, the

clutch-coils M being in series, as before. This combination of circuits is shown in Fig. 11. Advancing the contacts to a point where the brushes rest on line 12 12 gives the circuit combinations illustrated in Fig. 12—that is, say, the batteries and clutch-coils are in series relation, the armatures in multiple, with a portion of the field-coils cut out. When the brushes stand at a point intermediate the positions illustrated by the lines 8 8 and 9 9, the clutch-coils are out of circuit and the vehicle is free to coast.

What I claim as new, and desire to secure by Letters Patent of the United States, is—

1. The combination of a vehicle, a driving-wheel, a source of energy, a motive-power agency, worm-gearing between the motive-power agency and a driving-wheel, a regulator for said motive-power agency, and means controlled by said regulator for connecting and disconnecting the worm-driving mechanism from the driving-wheel.

2. In a vehicle, the combination of a stationary axle, a driving-wheel sleeved thereon, a mass of magnetic material arranged to move with the wheel, an energizing magnet-coil mounted on the stationary axle, a magnetic keeper sleeved on the axle, means for rotating said keeper, a motor, and means for including the energizing-coil in circuit with the motor whenever it is receiving current.

3. In a vehicle, the combination of a stationary axle, a casing rigidly secured thereto, a driving mechanism inclosed in said casing, a motor supported by said casing, gearing between said motor and the driving mechanism located within the casing, and a flexible nose suspension for the motor.

4. In a vehicle, the combination of an axle, a driving-wheel mounted thereon, a casing rigidly mounted on the rear axle, an electromotor supported by said casing, gearing between the motor and the driving-wheel located within the casing, a vehicle-body, a supporting-spring between the vehicle-body and the axle, and a socket formed in said casing in which said spring is seated.

5. In a vehicle, the combination of an axle, a casing mounted on said axle, a vehicle-body, an elliptic spring between said vehicle-body and the casing, a socket carried by said casing and arranged to receive the under side of the spring, an electromotor having a vertically-extending armature-shaft mounted on said casing, and a bracket carried by the vehicle-body for supporting the nose end of the motor.

6. In a vehicle, the combination of a source of electric supply, a pair of motors for propelling the vehicle, a magnetic clutch between each motor and its driving-wheel, and a single controller for coupling the motor-coils in different relations for speed changes, and for maintaining the clutch-coils in fixed relation under all changes in motor combinations.

7. In a vehicle, the combination of a source of electric supply, a pair of motors for propelling

- ling the vehicle, a magnetic clutch between each motor and a driving wheel or wheels, a controller, contacts thereon for effecting various combinations of the motor-windings, and 5 contacts also on said controller which are so arranged that whenever the motor-circuit is completed the circuit through the magnetic clutches is also completed and in the same direction.
10. 8. The combination of a stationary axle, a casing rigidly mounted thereon, a motor mounted on the casing in such a manner that its armature-shaft extends at right angles to the plane of the axle, a vehicle-body, a sup- 15 porting-spring between the axle and the body, a bracket secured to the body, and a flexible connection between the motor and the bracket.
9. The combination of a driving-wheel, a 20 shaft therefor, a source of energy, a motor having its driving-shaft located at right angles to the wheel-shaft, worm-gearing between the wheel and the motor, a rotating element concentrically mounted with respect to the axle 25 and forming a support for one part of the worm-gearing, a second element secured to the driving-wheel, means for operatively connecting the two elements, and a regulating device for controlling the speed of the motor 30 and throwing the two elements into and out of operative relation.
10. In an electric motor, a worm driven

thereby, a worm-wheel meshing with the worm, a mass of magnetic material forming a support for the worm-wheel, a wheel driven 35 by the motor, a mass of magnetic material moving with the wheel, an energizing-coil, and a single controller for changing the relation of the motor-coils to vary the speed of the motor and energizing the coil. 40

11. In combination, an axle, a support rigidly mounted thereon, an electric motor mounted on the support and having its driving-shaft mounted at right angles to the shaft, worm-gearing between the axle and the motor, and a clutch-coil which is included in the motor-circuit and is broken each time the supply of energy to the motor is interrupted. 45

12. In combination, an axle, an armature mounted thereon, a worm-wheel secured to 50 the armature, a worm meshing with the wheel, a gear-casing which is rigidly secured to the axle and incloses both the worm-wheel and the worm, a motor mounted on the casing and connected to the worm, and an elastic means 55 for decreasing the tendency of the motor to revolve around the axle.

In witness whereof I have hereunto set my hand this 30th day of October, 1900.

HERMANN LEMP.
